Primary Examiner—Janice E Seeger*Assistant Examiner*—Mary Ann Calabrese(74) *Attorney, Agent, or Firm*—Kilpatrick, Stockton, LLP(57) **CLAIM**

The ornamental design for an oval exit sign, as shown and described.

DESCRIPTION

FIG. 1 shows a top perspective view of an oval exit sign according to the present invention.

FIG. 2 shows a front view of the oval exit sign of FIG. 1.

FIG. 3 shows a right side view of the oval exit sign of FIG. 1, the left side view being the same.

FIG. 4 shows a rear view of the oval exit sign of FIG. 1.

FIG. 5 shows a top view of the oval exit sign of FIG. 1; and, FIG. 6 shows a bottom view of the oval exit sign of FIG. 1.

Portions or features of the oval exit sign shown in broken lines in the drawings form no part of the claimed design.
